The ornamental design for a prefabricated building, as shown and described.

DESCRIPTION

FIG. 1 is a front elevational view of a prefabricated building in accordance with my new design;

FIG. 2 is a rear view of the prefabricated building in accordance with my new design of FIG. 1;

FIG. 3 is a top plan view of the prefabricated building in accordance with my new design of FIGS. 1 to 2;

FIG. 4 is a bottom plan view of the prefabricated building in accordance with my new design of FIGS. 1 to 3;

FIG. 5 is a left side elevational view of the prefabricated building in accordance with my new design of FIGS. 1 to 4;

FIG. 6 is a right side elevational view of the prefabricated building in accordance with my new design of FIGS. 1 to 5;

FIG. 7 is a rear, right and top side perspective view of the prefabricated building in accordance with my new design of FIGS. 1 to 6; and,

FIG. 8 is a front, left and top side perspective view of the prefabricated building in accordance with my new design of FIGS. 1 to 7.

The oblique line shading in FIGS. 1-3 and 5-8 illustrates a translucent or transparent portion of the prefabricated building.
